GAME APPARATUS

Gérard Madieu, Monaco, Monaco

Application February 26, 1937, Serial No. 128,041
In France January 13, 1937

5 Claims. (Cl. 273—138)

This invention relates to a game apparatus and a principal object is to provide a simple, practical, dependable and unique apparatus capable of functioning as an adjunct to any suitable or appropriate game such as a game involving a number of players whose individual movements or progression on, for example, a marked-off game board have to be determined; among other objects is the provision of a game apparatus utilizing, in a unique and intriguing manner, certain forces of rotation and of rolling action and capable as desired of control by such degree of skill as the player may be able to exert in the effort to determine the magnitude or value of his turn at the game. To best carry out such objects as these, I aim to provide a game apparatus comprising a cup shaped receptacle provided at its lower central portion with a certain number of small recesses or like cavities and a plurality of balls; which are distinguished from one another by suitable means, such as different colours and/or sizes, numbers, notches or other indications, etc.

When the balls are set in movement in the cup and allowed to stop they will come together at the bottom of the latter and be retained in said recess, so that they will stand in a certain order determined by hazard on the figure or design formed by said recess.

The points scored by the players will be based upon the relative position or positions of one or more given balls, in the figure formed by the balls.

In a preferred embodiment, the said cup has three recesses and three balls are used.

The movement of the balls may be effected either by rotating the cup, or by the direct throwing of the balls in a stationary cup.

The said game apparatus, in order to evaluate the figure formed by the balls, is completed by a score indicating chart upon which are represented on the one hand the different figures which may be formed by the balls in the cup and also any suitable lines, circumferences or the like, combined with said figures in such way that by the positions of the balls in the cup, the scoring points of the different players are automatically indicated.

In the accompanying drawing, which is given solely by way of example:

Fig. 1 is a diagrammatic vertical section of a form of construction of a game apparatus in accordance with the invention.

Fig. 2 is a corresponding plan view.

Fig. 3 shows the corresponding score indicating table.

In the embodiment shown in Figs. 1 and 2, the apparatus comprises a concave receptacle 1 of shallow form, which is rotatably mounted, by means of an axle 2 and a ball bearing 3, upon a base 4. A pin 5, urged by a spring 6 mounted in a lateral support 7, enters an aperture 8 in the edge of the said recipient 1, and will thus stop this latter in a given angular position, after it has been set in rotation and has lost its kinetic energy after making a certain number of revolutions depending upon the force which has been thus applied.

In the bottom of the said cup 1 are formed three shallow circular recesses 9, 10, 11 which may have any desired position, but are preferably arranged, as shown, in such way that their centers are located at the apices *a*, *b*, *c*, of an equilateral triangle.

Any desired reference mark or indexing means such as the arrow 16 (Fig. 2) is provided on the cup, preferably in radial alignment with one of the recesses.

The apparatus is completed by three balls 12, 13, 14, which can be distinguished from one another by any desired means. In the present case, the three balls have the same diameter, and they can be recognized by their colour. For instance, the ball 12 is white, the ball 13 is blue, and the ball 14 is red. The balls preferably have such a diameter that they will touch each other when they stand in the respective recess 9, 10, 11, as shown in Fig. 2.

When the cup is rotated and then left to itself the balls will roll upon the surface, and when the cup has been brought to rest by the stop pin 5, they will come together at the bottom by the effect of gravity, and drop into the recesses 9, 10, 11, respectively.

With three recesses positioned at the apexes of an equilateral triangle as shown in Figure 2 and with three differently colored balls capable of being brought to rest in the respective recesses, the balls will thus be able to take such relative positions with respect to the arrow 16 that six different combinations or figures can be obtained.

The invention comprises also a score indicating chart 17 (Fig. 3) showing the said combinations as indicated at A, B, C, D, E, F. Arrows 18 on said chart correspond to the arrow 16 of the cup and the respective positions which the balls can take are shown by white circles (12) 55

blue circles (13) and red circles (14) arranged tangentially to each other.

The six combinations are as follows:

Combination A.—The white ball 12 is at the top, 5 in the recess 9.

The red ball 14 at the bottom, on the right, in the recess 11. And the blue ball 13 at the bottom, on the left, in the recess 10.

The whole set of combinations is shown below:

	Top	Bottom	
		Left	Right
Combination:			
A	12	13	14
B	12	14	13
C	14	12	13
D	14	13	12
E	13	14	12
F	13	12	14

In the embodiment shown in Fig. 3, the combinations A and B are shown side by side, C and 25 D are shown below side by side, and D and E are shown at the base of the chart, also side by side, with a point of contact between the inner circles of the combinations A and B, C and D, E and F. Moreover, a circumference 19 is shown 30 on each group, said circumference passing through the point of contact between the three balls in each group.

The chart like that of Figure 3, for interpreting or translating the possible geometric 35 figures which the balls can be made to set up may be used for many game combinations. For example, the several players may take turns in manipulating the balls and the cup and the six combinations A to F of Figure 3 may be given 40 appropriately differing numerical values such as, for example, from 1 to 6, respectively. Accordingly, if a player achieves the combination B that could mean that he may make two moves in whatever game the apparatus, including the 45 chart, is functioning, and so on. For that matter, some of the combinations may be given negative values to indicate retrograde movement in the particular game being played. Thus, the game being played might be a game like "par- 50 chesi" or "backgammon." Many other game combinations can, of course, be devised.

Obviously, the said invention is not limited 55 to the embodiment shown and described. The stop pin 5 may be dispensed with. It has however the advantage of stopping the cup in a position which is fixed in space, which facilitates the control of the game by the players. When the stop pin 5 is used, it will be appreciated that the stoppage of the rotating receptacle 1 may be 60 relatively sudden in which case the rolling around of the balls is given, relatively, a substantial impetus and in such case the player can exercise his efforts at skill by the initial rotary movement that he gives the cup and that may 65 be set into rotation at, for example, high speed or low speed, and likewise, also, the player may set the stop pin into action at any point in the deceleration of the cup. If, as above noted, the stop pin is dispensed with, the rotary motion 70 of the cup, initially achieved at any desired value as the player's judgment and skill may direct, may be halted or decelerated in any suitable way, even manually, thus affording the player the opportunity of exercising skill and 75 judgment in the rate at which the cup is decel-

erated or the point in its deceleration at which it is completely halted, or both, the result as set up by the balls depending upon these factors and their variations as determined by the skill and judgment of the player.

The cup 1 need not have a rotary motion, and for the more simple playing, it may be moved by hand.

The cup 1 may also be held stationary, in which case the balls are thrown by hand or by a stream 10 of air, or by any other means.

In order to make a distinction between the balls, use may be made of any desired characteristics such as colours, numbers, different sizes, perforations, various marks, or the like.

The arrangement of the combinations on the score indicating chart 17 may be different from the one represented, and may consist of separate circles, inverted combinations, different positions, etc. Some of the circles of a combination could be superposed upon circles of another combination and each combination could have contacting points with a plurality of other combinations. Different values could be put upon these different arrangements and different interpretations given them according to the particular game being played.

Thus, it will be seen that there has been provided in this invention a game apparatus in which the various objects above noted, together 30 with other thoroughly practical advantages, are successfully achieved. The action of the mechanism is unique and intriguing, the apparatus is of wide adaptability, and the exercise of the player's skill may be brought into play to any 35 desired extent.

As many possible embodiments may be made of the above invention and as many changes might be made in the embodiment above set forth, it is to be understood that all matter here- 40 inbefore set forth, or shown in the accompanying drawing, is to be interpreted as illustrative and not in a limiting sense.

Having now described my invention what I claim as new and desire to secure by Letters 45 Patent is:

1. A game apparatus comprising a receptacle provided at its lower central part with a number of recesses arranged at the apexes of a polygon and leaving thereabout a circular smooth path, indexing means forming a point of orientation with respect to said polygon, and a set of individually distinguishable balls in the same number as the said recesses, adapted to freely roll in said receptacle along said circular smooth 50 path and to enter respectively into said recesses to be retained therein by their own weight, whereby said balls and said recesses coact to set up according to which distinguishable balls enter which recesses, any one of a plurality of distinguishing 55 polygonal arrangements with respect to said point of orientation formed by said indexing means.

2. A game apparatus comprising a receptacle provided at its lower central part with a number of recesses arranged at the apexes of a polygon and leaving thereabout a circular smooth path, indexing means forming a point of orientation with respect to said polygon, and a set of individually distinguishable balls in the same 70 number as the said recesses, adapted to freely roll in said receptacle along said circular smooth path and to enter respectively into said recesses to be retained therein by their own weight, the recesses being so located that the balls are in 75

contact with each other in the lower part of the receptacle when they are retained in the respective recesses, whereby said balls and said recesses coact to set up according to which distinguishable balls enter which recesses, any one of a plurality of distinguishable polygonal arrangements with respect to said point of orientation formed by said indexing means.

3. A game apparatus comprising a receptacle provided at its lower central part with a number of recesses arranged at the apexes of a polygon and leaving thereabout a circular smooth path, indexing means forming a point of orientation with respect to said polygon, and a set of individually distinguishable balls in the same number as the said recesses, adapted to freely roll in said receptacle along said circular smooth path and to enter respectively into said recesses to be retained therein by their own weight, and means for rotatably supporting the receptacle, whereby said balls and said recesses coact to set up according to which distinguishable balls enter which recesses, any one of a plurality of distinguishable polygonal arrangements with respect to said point of orientation formed by said indexing means.

4. A game apparatus comprising a receptacle provided at its lower central part with a number of recesses arranged at the apexes of a polygon

and leaving thereabout a circular smooth path, indexing means forming a point of orientation with respect to said polygon, and a set of individually distinguishable balls in the same number as the said recesses, adapted to freely roll in said receptacle along said circular smooth path and to enter respectively into said recesses to be retained therein by their own weight, and means for rotatably supporting the receptacle and means adapted to stop the rotary receptacle in a given angular position, whereby said balls and said recesses coact to set up according to which distinguishable balls enter which recesses, any one of a plurality of distinguishable polygonal arrangements with respect to said point of orientation formed by said indexing means.

5. A game apparatus comprising a receptacle provided with a circular interior surface with three recesses arranged in substantially an equilateral triangle, whose center substantially coincides with the center of said surface, and a plurality of individually distinguishable balls capable upon relative movement between them and said receptacle of ultimately coming to rest in recesses at the apexes of said triangle and in coaction with said recesses to form any one of a number of distinguishable triangular relations with respect to a given point of orientation.
